US00D837325S

(12) **United States Design Patent** (10) **Patent No.:** **US D837,325 S**
(45) **Date of Patent:** **** Jan. 1, 2019**

(54) **GOLF ALIGNMENT TOOL**

(71) Applicant: **Geoffroy Dardenne**, Parcieux (FR)

(72) Inventor: **Geoffroy Dardenne**, Parcieux (FR)

(**) Term: **15 Years**

(21) Appl. No.: **29/615,044**

(22) Filed: **Aug. 25, 2017**

(51) LOC (11) Cl. **21-02**

(52) U.S. Cl.

USPC **D21/793**

(58) **Field of Classification Search**

Primary Examiner — Catherine A Tuttle

(74) Attorney, Agent, or Firm — Scarinci Hollenbeck; Jason LaBerteaux

(57) **CLAIM**

The ornamental design for the golf alignment tool, as shown and described.

DESCRIPTION

FIG. 1 is a left perspective view in a closed configuration showing my new design;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof;

FIG. 8 is a top perspective view in an open configuration showing the design;

FIG. 9 is a bottom perspective view thereof;

FIG. 10 is a front view of the lower half, shown separately for clarity of disclosure;

FIG. 11 is an inverted front view of the upper half, shown separately for clarity of disclosure;

FIG. 12 is a top view thereof;

FIG. 13 is a bottom view thereof;

FIG. 14 is a top perspective view in an open configuration and with supports extended; and,

FIG. 15 is a bottom view thereof with supports extended. No claim is made to the surface pattern shown in broken lines.

1 Claim, 8 Drawing Sheets
